DESIGN FOR A COMBINED STOVE TOP, BACK GUARD MEMBER, LIGHTING UNIT, AND SHADE

Stephen Leonard, Detroit, Mich., assignor to
Detroit Vapor Stove Company, Detroit, Mich.,
a corporation of Michigan

Application May 24, 1933. Serial No. 48,204

Term of patent 3½ years

To all whom it may concern:

Be it known that I, STEPHEN LEONARD, a citizen of the United States, residing at 237 North Lenox Avenue, Detroit, in the county of Wayne and State of Michigan, have invented a new, original, and ornamental Design for a Combined Stove Top, Back Guard Member, Lighting Unit, and Shade, of which the following is a specification, reference being made to the accompanying drawing forming part thereof.

The drawing illustrates a perspective view of

my combined top and back guard plate for a stove, and showing the general embodiment of a clock as a part of the back guard and a lighting unit and shade positioned above the back guard for illuminating the top of the stove.

I claim:

The ornamental design for a combined stove top, back guard member, lighting unit, and shade, as shown and described.

STEPHEN LEONARD.
